UNITED STATES PATENT OFFICE

91,666

DESIGN FOR AN ANNOUNCEMENT BOARD

Thomas A. Keen, St. Louis, Mo.

Application May 5, 1933, Serial No. 48,023

Term of patent 14 years

To all whom it may concern:

Be it known that I, THOMAS A. KEEN, a citizen of the United States, residing at St. Louis, Missouri, have invented a new, original, and ornamental Design for an Announcement Board, of which the following is a specification, reference being had to the accompanying drawing, forming a part thereof.

I claim:

The ornamental design for an announcement board as shown.

THOMAS A. KEEN.
